(57) **CLAIM**

The ornamental design for an indicia reading device, as shown and described.

DESCRIPTION

FIG. 1 is a perspective view of an embodiment of the indicia reading device;

FIG. 2 is a front elevation view of the embodiment of the indicia reading device;

FIG. 3 is a rear elevation view of the embodiment of the indicia reading device;

FIG. 4 is a left side elevation view of the embodiment of the indicia reading device;

FIG. 5 is a right side elevation view of the embodiment of the indicia reading device;

FIG. 6 is a top plan view of the embodiment of the indicia reading device;

FIG. 7 is a bottom plan view of the embodiment of the indicia reading device;

FIG. 8 is another perspective view of the embodiment of the indicia reading device;

FIG. 9 is yet another perspective view of the embodiment of the indicia reading device;

FIG. 10 is yet another perspective view of the embodiment of the indicia reading device; and,

FIG. 11 is yet another perspective view of the embodiment of the indicia reading device.

Any broken lines shown in the drawings of the indicia reading device are for illustrative purposes only and form no part of the claimed design.
